UNITED STATES PATENT OFFICE.

EARL L. McKIMM, OF KANSAS CITY, MISSOURI.

DESIGN FOR A HEEL.

56,726.

Specification for Design.

Patented Dec. 7, 1920.

Application filed June 12, 1920. Serial No. 388,654. Term of patent 7 years.

To all whom it may concern:

Be it known that I, EARL L. McKIMM, a citizen of the United States, residing at Kansas City, in the county of Jackson and State of Missouri, have invented a new, original, and ornamental Design for Heels, of which the following is a specification, reference being had to the accompanying drawing, forming part thereof.

The figure is a perspective view directed to the bottom of a heel, showing my new design.

I claim—

The ornamental design for a heel, as shown.

EARL L. McKIMM.
